GOBLET

Marvin G. Yutzey, Moundsville, W. Va., assignor
to Fostoria Glass Company, Moundsville,
W. Va. a corporation of West Virginia

Application December 28, 1949, Serial No. 6,882

Term of patent 14 years

(Cl. D36—8)

To all whom it may concern:

Be it known that I, Marvin G. Yutzey, a citizen of the United States of America, residing at Moundsville, in the county of Marshall and State of West Virginia, have invented a new, original, and ornamental Design for Goblet, of which the following is a specification, reference being had to the accompanying drawing, forming a part thereof, wherein:

Fig. 1 is a side elevational view of a goblet, showing my new design;

Fig. 2, a horizontal sectional view taken on the line 2—2 of Fig. 1, looking in the direction indicated by the arrows; and,

Fig. 3, a horizontal sectional view taken on the line 3—3 of Fig. 1, looking in the direction of the arrows.

The dominant features of the goblet reside in the ornamentation on the bowl portion thereof as shown.

I claim:

The ornamental design for a goblet, as shown and described.

MARVIN G. YUTZEY.
